UNITED STATES PATENT OFFICE.

WILLIAM STANLEY, JR., OF GREAT BARRINGTON, MASSACHUSETTS, AS
SIGNOR TO GEORGE WESTINGHOUSE, JR., OF PITTSBURG, PA.

INDUCTION-COIL.

SPECIFICATION forming part of Letters Patent No. 349,617, dated September 21, 1886.

Application filed February 10, 1886. Serial No. 191,406. (No model.)

To all whom it may concern:

Be it known that I, WILLIAM STANLEY, Jr., a citizen of the United States, residing in Great Barrington, in the county of Berkshire and 5 State of Massachusetts, have invented certain new and useful Improvements in Induction-Coils, of which the following is a specification.

My invention relates to the class of apparatus employed for converting electric energy 10 from currents of a given potential to currents of a different potential or different quantity.

In the conversion of electrical energy from currents of a lower to a higher potential, and vice versa, by means of induction-coils, it is 15 desirable that the quantity of iron acted upon by the currents in the primary circuit, and in turn reacting upon the coils in the secondary circuit, should be as great as possible, and that the iron itself should be divided into thin 20 laminae or plates, rather than united in a solid mass, and it is also desirable that the parts be so organized as to render the construction of the coil as simple as possible.

The object of the invention is, therefore, to 25 provide a form of induction-coil in which the magnetizable portion is formed of thin plates of soft iron adapted to support the primary and secondary conductors in such manner that they shall be as nearly as possible surrounded 30 by magnetic material, and shall be so located that the currents traversing the primary shall be expended to the best advantage in magnetizing the iron, and that the magnetization and demagnetization of the iron shall be utilized 35 to the best advantage in establishing induced currents in the secondary coils.

The invention consists in winding the primary and secondary conductors upon a suitable form, which may with advantage be octagonal, and mounting upon the coil or core 40 of wires thus formed by the primary and secondary conductors annular disks or rings of magnetic material. These disks are applied by being formed with central openings of such 45 size as to receive the wire, and they are cut open upon one side. By springing the two ends thus formed laterally they are slipped over the core of wire, and thus caused to surround the conductors.

50 In another application of even date here-with, Serial No. 191,405, there is described an

inductorium resembling in some of its features that described and claimed herein.

In the accompanying drawings, Figure 1 is a plan view of an induction-coil constructed 55 upon this principle, and Fig. 2 is a cross-section of a portion of the same.

Referring to the figures, a' and a'' represent the terminals of the primary conductor A, and b' and b'' the terminals of the secondary conductor B. These conductors are wound upon a suitable forming-block into an annulus, which may be of circular, or, as shown in the drawings, of an octagonal form. The ends of the conductors are secured to suitable binding-posts. The conductors having been thus formed, the iron to be acted upon by the primary conductor, and in turn to act upon the secondary coils, is placed in position. It consists of a series of disks, $c c$, which are separately formed. Each disk has an opening through the center, as shown at d , of such size as to admit the core of wire, and a slot or opening, d' , is cut from the center to the periphery. By springing the ends e' and e'' aside 75 or in opposite directions the disks may be placed, one at a time, upon the coils. They are preferably separated from each other by non-magnetic material, for the purpose of rendering the coil capable of more rapid magnetization 80 and demagnetization.

I claim as my invention—

1. The combination, substantially as herein-before set forth, with the primary and secondary conductors of an induction-coil wound to 85 form an annulus, of a series of slotted plates of soft iron, through which the conductors extend.

2. The combination, substantially as herein-before set forth, of a series of magnetically-separated disks or plates of soft iron, each having a radial slot, and primary and secondary conductors extending axially through the same, substantially as described.

In testimony whereof I have hereunto subscribed my name this 28th day of January, A. D. 1886.

WILLIAM STANLEY, JR.
